(57) **CLAIM**

The ornamental design for a portion of a bottle with surface ornamentation, as shown and described.

DESCRIPTION

FIG. 1 is a front elevation view of a portion of a bottle with a surface ornamentation showing our new design, the rear, left and right sides being a mirror image;

FIG. 2 is a top plan view thereof;

FIG. 3 is a bottom plan view thereof;

FIG. 4 is a front elevation view of an alternate embodiment of FIG. 1, the rear, left and right sides being a mirror image;

FIG. 5 is a top plan view of FIG. 4; and,

FIG. 6 is a bottom plan view of FIG. 4.

The broken lines are for illustrative purposes only and form no part of the claimed design.
